NEILS A. NEILSEN, OF CUPERTINO, CALIFORNIA

GAP FILLER

Application filed May 11, 1929. Serial No. 362,353.

My invention relates to a device particularly adapted for filling gaps in earth ridges formed for irrigating purposes.

It is the object of the invention to provide a device of the character indicated that will load quickly; that will not tip in loading; that may be dumped accurately and quickly without breaking down any of the ridge; that will be light, strong, durable, economical to manufacture, positive in operation, and highly efficient in its practical application.

The drawing shows a perspective view of a device embodying my invention.

In construction this device I first provide a pair of side plates as 1—1, preferably oblong and rectangular in side elevation, and between these plates and rigidly secured to them to form an integral whole, is an angularly disposed scoop plate 2 fitted with teeth 3, this plate extending from the upper edges to the lower edges of the side plates and dividing them into two equal parts as shown.

Pivottally mounted as at 4 on the centers of the two plates 1—1, is a draw bar 5, this bar extending forwardly of the plates and being fitted with a bar 6 pivotally mounted thereon and carrying a pin 7 to which is attached an operating cable 8. Extending inwardly from the opposing sides of the bar 6 are stop pins 9 adapted to engage stops 10 disposed on the upper forward and lower rear edges of the two plates 1—1, and turned inwardly from the lower ends of the bar 6 are fingers 11 adapted to hold the bar 6 in the position shown against the backward pull of the spring 12 connected to the bar 6 and the draw bar 5.

It is obvious from the foregoing description that when the device is being drawn over loose ground the soil will accumulate on the front surface of the angular scoop plate 2. When the operator wishes to dump the device he merely pulls upon cable 8 thereby displacing the stops 9—10 and permitting the forward corners of the plates 1—1 to dig into the ground and cause the said plates to describe a complete one-half revolution, the scoop plate depositing its load on the ground and turning over it so as to bring its opposite edge into working contact with the ground.

When the operator releases the cable 8 the spring 12 and stop 11 cooperate to hold the stop pins 9 in position to engage the stops 10 and hold the plates in the new position.

By constructing the device to make a half turn instead of a complete revolution it has more time for loading and turns over the ridges without breaking them down, besides operating more smoothly.

It is to be understood, of course, that while I have herein shown and described but one specific embodiment of the invention, changes in form, construction and method of assembly and operation may be made within the scope of the appended claim.

I claim:

A device of the character indicated comprising a pair of vertically positioned rectangular side plates, a flat spacing plate rigidly mounted thereon and therebetween and terminating at the upper and lower edges thereof, and angularly positioned relative to a horizontal plane, a draw bar pivotally connected to the plates, means for normally holding the plates in fixed relation to the draw bar, and means for permitting the rotation of the plates relative to the draw bar.
